DESIGN FOR A BACK REST FOR A STUDIO COUCH OR SIMILAR ARTICLE OF FURNI- TURE

Charles A. Stuart, Kenosha, Wis., assignor to Simmons Company, New York, N. Y., a corporation of Delaware

Application November 29, 1935, Serial No. 59,816

Term of patent 14 years

To all whom it may concern:

Be it known that I, Charles A. Stuart, a citizen of the United States and a resident of Kenosha, in the county of Kenosha and State of Wisconsin,
have invented a new, original, and ornamental Design for a Back Rest for a Studio Couch or Similar Article of Furniture, of which the following is a specification, reference being had to the accompanying drawing, forming a part thereof.

The drawing is a perspective view showing a back rest embodying my new design.

I claim:

The ornamental design for a back rest for a studio couch or similar article of furniture, substantially as shown.

CHARLES A. STUART.
